Garnett & Smith & Henry Brown, of Philadelphia, Pa:

Assignors to —

Leibrandt, McDowell & Co. of the same place.

Letters Patent No. 961 - Dated Oct. 20th 1857.

The schedule referred to in these Letters Patent & making part of the same.

To all whom it may concern.

Be it known, that we Garnett & Smith and Henry Brown, both of the City of Philadelphia, and State of Pennsylvania, have invented or produced a new and original design for a small parlor stove, termed the "Ivy Stove", and we do hereby declare that the following is a full and exact description of the same, reference being had to the accompanying drawing, and to the letters of reference marked thereon.

Fig: 1. is a view of the front plate of the ivy stove, with doors for the fire place and ash pit.

Fig: 2. a view of the back plate.

Fig: 3. plan view of the bottom plate.

Fig: 4. plan view of the top plate.

Fig: 5. view of the side plates.

Fig: 6. sectional view (full size) of the moulding on the edge of the top plate.

Fig: 7. an enlarged view of the run, and

Fig: 8. a general view of the front of the stove in outline. Similar letters refer to similar parts throughout the several views.

A. is the ornamented front plate of the stove to which are hung the doors a. a. of the fire place, and to which may be attached, when required, the door b. of the ash pit.

B. the back plate of the stove, with an oval opening at the top for the flue pipe.

C. the bottom plate with the hearth in front.

D. the top plate, the moulding on the edge of which is shown at Fig: 6.

E. is one of the ornamented side plates.

F. is the run with cover d.

We claim the combination and arrangement of ornamental figures and forms represented, forming together an ornamental design for a Parlor Stove.
